UNITED STATES PATENT OFFICE.

FRANK M. ARCHER, OF BROOKLINE, MASSACHUSETTS, ASSIGNOR TO THE MOXIE COMPANY, OF BOSTON, MASSACHUSETTS, A CORPORATION OF MAINE.

DESIGN FOR A HOLDER FOR ASH TRAYS OR SIMILAR ARTICLES.

60,973.

Specification for Design.

Patented May 23, 1922.

Application filed April 26, 1921. Serial No. 464,697. Term of patent 14 years.

To all whom it may concern:

Be it known that I, FRANK M. ARCHER, a citizen of the United States, residing at Brookline, in the county of Norfolk and State of Massachusetts, have invented a new, original, and ornamental Design for a Holder for Ash Trays or Similar Articles, of which the following is a specification, reference being had to the accompanying drawing, forming a part hereof.

The figure is a side view of the holder.

I claim:

The ornamental design for a holder for ash trays or similar articles, as shown.

Signed at Boston, Massachusetts, this 25th day of April, 1921.

FRANK M. ARCHER.
